WEEDER OR THE LIKE

Thomas I. Mendenhall, Chicago, Ill.

Application August 10, 1959, Serial No. 57,126

Term of patent 14 years

(Cl. D35—2)

The bottom and rear of the weeder are substantially plain, except for an indentation corresponding to the rib shown in Figures 1 and 3.

The characteristic feature of my design for the weeder as shown resides in the lateral extension having rearwardly extending teeth therein.

I claim:

The ornamental design for a weeder or the like, substantially as shown and described.
